UNITED STATES PATENT OFFICE

OLIVER P. GREENSTREET, OF OWENSVILLE, MISSOURI

ANTIFREEZING LIQUID

No Drawing. Application filed September 4, 1930. Serial No. 479,805.

This invention relates to the production of an anti-freezing liquid adapted to be used in the radiators of automobiles in place of alcohol, glycerine or other "anti-freeze" mixtures now on the market.

The object of my invention is to provide an antifreezing mixture which is relatively cheap, which is not dangerous and which will prevent rust or corrosion of any part or parts of the radiator.

My anti-freezing liquid consists of petroleum in the form of coal oil or kerosene to which has been added oil of mirbane (mono-mitro-benzene, $C_6H_5NO_2$), this mixture being brought to a boiling point and boiled for approximately thirty minutes or from thirty minutes to one hour in order to eliminate therefrom the lighter and more volatile fractions and thus raise the flash point of the kerosene. While I do not wish to be limited to any particular method or heating, preferably the mixture is heated by steam discharged through the tank containing the kerosene and mirbane or the mixture may be heated by a steam coil extending through the oil, but any other means for heating the oil, as for instance, by an electric coil or a stove may be used and be within the scope of this invention.

While in the usual separation of kerosene from crude oil, some of the higher boiling point fractions are eliminated, in ordinary kerosene, there still remains dangerous and readily volatilized fractions which must be eliminated before the oil can be used in a radiator. When petroleum is brought to a boiling point and kept at this point for some time, it throws off lighter fractions evidenced by the giving off of an exceedingly disagreeable odor. I find that after the oil is boiled for from thirty to sixty minutes, the odor ceases and no odor except that of ordinary kerosene can be noticed when the liquid is used in a car, no matter how hot the radiator may get. By bringing the oil to a boiling point and keeping it at this boiling point for approximately a half hour or more, I find that the oil is no longer dangerous as this heating of the kerosene eliminates the lighter and more volatile fractions which are par-

ticularly explosive and raises the flash point an appreciable amount.

By mixing oil of mirbane with kerosene, I secure a great working range. Some grades of kerosene start to boil at 180° F. while oil of mirbane does not boil until the temperature is raised to 408° F. so that by mixing kerosene with oil of mirbane, I raise the boiling point to above that of water or above kerosene itself. By adding the proper quantity of oil of mirbane, I can raise or lower the boiling and freezing point but preferably I will use a mixture that will not freeze until -43° F. has been reached and which shall not boil until 322° F. has been reached. This high boiling point is very important as motors often get hot enough to boil away the water in the radiator.

By using this mixture, the motor will never get hot enough to cause the mixture in the radiator to boil. The oil of mirbane starts to freeze around zero. The kerosene does not freeze until a temperature of 75° below zero is reached. Thus by boiling the kerosene and adding oil of mirbane, I secure a liquid particularly adapted to the radiators of automobiles as it will not freeze and will not boil except under exceptional circumstances.

While I have before referred to mixing oil of mirbane with the kerosene before boiling the latter, I do not wish to be limited to this as the oil of mirbane might be added to the liquid after the kerosene has been boiled.

I find that by boiling the oil as stated, I raise its boiling point to approximately that of water. The oil while acting as a cooling agent in the radiator will not freeze under practically any circumstances and will prevent rust and corrosion of any part or parts of the radiator.

While I do not wish to be limited to any particular proportion of the oil of mirbane relative to the kerosene, I am using and I find most effective one part of oil of mirbane to ten parts kerosene, but obviously these proportions may be varied so as to make the mixture freeze or boil at different freezing or boiling points.

In addition to this, this mixture helps to

clean the radiator and eliminate any rust or other accumulation which has previously formed therein.

I claim:—

5 An anti-freezing liquid for use in radiators consisting in kerosene, in which the high boiling point fractions have been eliminated, and oil of mirbane.

10 In testimony whereof I hereunto affix my signature.

OLIVER P. GREENSTREET.
